UNITED STATES PATENT OFFICE.

HENRY P. PROUD, OF PHILADELPHIA, PENNSYLVANIA.

AUTOMATIC STOP FOR TALKING-MACHINES.

1,274,444.

Specification of Letters Patent.

Patented Aug. 6, 1918.

Application filed March 27, 1917. Serial No. 157,664.

To all whom it may concern:

Be it known that I, HENRY P. PROUD, a citizen of the United States, residing in the city and county of Philadelphia, State of Pennsylvania, have invented a new and useful Automatic Stop for Talking-Machines, of which the following is a specification.

My invention consists of an attachment for a talking machine embodying novel means for causing the engagement automatically of a brake member with the turn table of such machine for stopping the latter promptly on the termination of a piece played.

15 It consists also of mechanism adapting the attachment to be set relatively to the number of convolutions on records so that said attachment is operative relatively to records of playing pieces of different lengths.

20 The invention is satisfactorily illustrated in the accompanying drawing, but the important instrumentalities thereof may be varied, and so it is to be understood that the invention is not limited to the specific details shown and described.

Figure 1 represents a plan view of a stop-attachment for a talking machine embodying my invention.

Fig. 2 represents a longitudinal section of a portion on line 2—2 Fig. 1.

Fig. 3 represents a transverse section of a portion on line 3—3 Fig. 1.

Fig. 4 represents a plan view of a detached portion of the attachment.

Fig. 5 represents a perspective view of certain members of the attachment in a different position from that shown in Fig. 1.

Similar numerals of reference indicate corresponding parts in the figures.

40 Referring to the drawings,

1 designates the turn table of a talking machine, the same being mounted on the top of the cabinet of such machine as usual. 2 designates a bar or base which is supported on said top and having a side plate 3 which extends angularly therefrom over said top.

45 4 designates a disk like head which is located below the turn table and rotatably mounted on said bar 2 by the pivot 5, said head having in its periphery the recess 6, and on said periphery the upturned lugs 7, the upturned lug 8, and the outturned projection 9.

50 On the periphery of the plate 3 are the upturned lugs 10, 11, and 12, said lugs and the

projection 9 being spaced on the respective members relatively to each other for purposes to be hereinafter described.

13 designates what I denominate a brake shoe which is formed of leather, rubber, or other suitable pliable material, a portion of the same resting on the face of the head 4 and being secured thereto by the screw 14, and having its sides embraced by the lugs 7, so as to be held firmly in position, a portion of said brake shoe projecting from the periphery of the head, so as at a proper time to engage frictionally the depending rim 15 of the turn table 1, and stop the rotation of the latter.

70 16 designates an elbow lever which is connected with the bar 2 by the pivot 17, one limb 18 of said lever extending over the bar 2 and having on its free end the laterally turned nose 19 which is adapted to enter the recess 6 in the head 4 and lock the latter, whereby the brake shoe is held out of contact with the rim 15.

75 Connected with the lug 8 of the head 4 and the lug 11 of the plate 3 is the spring 21, whose object is to rotate said head when the latter is released of the nose 19.

80 Connected with the lug 12 of the plate 3 and the limb 18 of the elbow lever 16 is the spring 22 which is adapted to hold the nose 19 of said limb in engagement with the head 4 in the recess 6 in the latter.

85 On the pivot or pin 17 of the elbow lever and interposed between the head of said pivot and the adjacent portion of said elbow lever, and between said portion and the contiguous part of the bar 2 are the resilient washers 23 and 24 which serve to hold said lever properly separated from said bar and impart proper friction to the former.

90 Interposed between the top of the cabinet and the bar 2 is the bar 25, said bar 2 having therein the longitudinally-extending slot 26 which receives the headed screw or pin 27 which passes through said slot and one end of the bar 25 into the top of the cabinet, said bar 25 having thereon the index finger 28 which overhangs the bar 2 and points to either of the graduations 29 on the latter. The other end of the bar 25 has thereon the 100 longitudinally-extending slot 30 which receives the pivot 17 which is provided with a head which engages the underside of the bar 25 on opposite walls of said slot 30, it being noticed that by these means the bar 2 is con-

connected with the bar 25, but the former is permitted to slide on the latter and so be moved say to the right and left, whereby the limb 20 of the elbow lever may be set so as to be tripped relatively to the number of the spiral grooves or convolutions on the record so that when the end of said groove is reached the limb 20 will be tripped and the brake shoe caused to be operated sensitively when the piece on the record has been played, thus promptly stopping the rotation of the turn table and consequently of the record.

The extent of rotation of the head 4 is limited by the abutment of its projection 9 with the lug 10 on the plate 3, said members 10 and 9 forming a stop for the purpose designated.

It will be noticed that the horn 30* of the machine has thereon an arm 31, and the limb 20 of the elbow lever is so located on the top of the cabinet below the turn table as at a certain time to be in the path of said arm, consequently when the sliding bar 2 is moved as to set said limb relatively to the length of the piece to be played, and the head 4 is locked by the nose of the limb 18 of said elbow lever, the device is in operative condition.

When the playing of the piece is about to end, the arm 31 reaches the limb 20, and bears against the same, so as to trip it, whereby the nose 19 is withdrawn from the recess 6, and so the head 4 is rotated due to the action of the spring 21 bringing the brake shoe into frictional contact with the rim of the turn table, thus quickly stopping the latter, which, as is evident, is occasioned just as the playing of the piece is ended.

The head may be reset for the next piece to be played by rotating it in reverse direction, for which purpose said head is provided with the arm or lever 32 convenient for the purpose, the nose 19 then again dropping into the recess 6 and so controlling the disk against rotation until the elbow lever is

engaged and operated by the horn as previously described.

Having thus described my invention what I claim as new and desire to secure by Letters Patent, is:—

1. In a stop attachment for a talking machine, a rotatable head, a brake member thereon, a base, an elbow lever pivoted on said base and having means engageable with said head to lock the latter and the other limb movable independently of and adapted to be in the path of a movable member of said machine, means on said head and the base for causing rotation of the head, and means on said elbow lever and base independent of said rotating means and acting on the said arm of the elbow lever to hold the latter in engagement with said head, said base being slidably mounted.

2. In a stop attachment for a talking machine, a rotatable head, a base on which said head is rotatably mounted, a brake member on said head, means engageable with the periphery of said head for holding the same immovable, means for limiting the rotation of said head and means including a tone-arm for releasing said head to permit its movement, said base being adjustably mounted on a support whereby said releasing means may be set to records of different lengths and the brake automatically released by the tone-arm.

3. In a stop attachment for a talking machine, a rotatable head, a brake member thereon, a base member on which said head is mounted, said base member being slidably mounted on a support and provided with graduations, whereby the brake is automatically released by the tone arm, and an index finger on said support adapted to point to either of said graduations.

HENRY P. PROUD.

Witnesses:

HENRY J. WALTER,
JOHN A. WEIDERSHEIM.
